Thomas L. Wilder

ATTORNEY

UNITED STATES PATENT OFFICE.

HARRY M. JENNINGS, OF UTICA, NEW YORK.

AUTOMOBILE-WASHER.

1,142,966.

Specification of Letters Patent. Patented June 15, 1915.

Application filed June 21, 1913. Serial No. 774,993.

To all whom it may concern:

Be it known that I, HARRY M. JENNINGS, a citizen of the United States, residing at Utica, in the county of Oneida and State of New York, have invented certain new and useful Improvements in Automobile-Washers, of which the following is a specification, reference being had therein to the accompanying drawing.

10 My invention relates to an automobile cleaner and I declare the following to be a full, clear, concise and exact description thereof sufficient to enable any one skilled in the art to which it appertains to make 15 and use the same, reference being had to the accompanying drawings in which like reference characters refer to like parts throughout the specification.

The object of the invention is to provide 20 a simple, efficient device for cleaning automobiles.

The mechanism embodies a tube of any suitable dimensions made preferably of some light metal such as aluminum and adapted 25 to be connected at one end to a hose and at the other end to a brush, so that the water passing through the tube from the hose will aid the brush in cleaning the parts of an automobile. However, the device may be 30 employed in cleaning windows, or other like places, or it may be connected to any suitable air suction machine for vacuum cleaning purposes.

In the drawings, Figure 1 is a side elevation of the device as it would appear in 35 operation; Fig. 2 is an enlarged fragmentary view, showing parts in section; Fig. 3 is an enlarged plan view of a member employed to hold soap; Fig. 4 is an enlarged

40 fragmentary view, showing a section of a modified construction; Fig. 5 is an elevation of the view shown in Fig. 4; Fig. 6 is a perspective view of a special kind of brush, that may be employed; Fig. 7 is a section 45 taken on the line 7-7 of Fig. 4; Fig. 8 is an enlarged fragmentary view in section of a portion of the member for holding the soap, showing also immediate parts; Fig. 9 is a view reduced in size, showing the hose and 50 brush in combination with the apertured soap container illustrated in Figs. 4, 5 and 7.

Referring more particularly to the drawings, the invention embodies a tube —1— made preferably of some light metal such as 55 aluminum. The end 2 of tube —1— is screw threaded to be mounted to the

threaded end of a nozzle 3 of a hose 4. The opposite end of tube —1— or end 5 is also threaded, whereby there may be detachably held to said end 5, the tube portion 6 of a 60 brush 7. Tube —1— is enlarged at portion 8, which is shouldered at 9 and screw threaded at 10 for the reception of the portion 11 of tube —1—. The enlarged portion 8 is intended to house members 12—12, 65 which are made spoon shaped for holding a cake of soap 13, therebetween. Members 12—12 are adjusted relative to each other, whereby they may, to any desired degree, shield the cake of soap 13 from the water 70 that passes through the tube —1—, by means of screws 14—14. The screws 14 work in correspondingly threaded bores in the enlarged portion 8 of the tube —1— and are headed at 16, which heads rest loosely in 75 recesses 17 of the members 12, so that said screws 14 may turn independently of the members 12. In order to aid in urging members 12 normally toward each other, there is employed about the screws 14 coiled 80 springs 18—18. Screws 14 are furthermore locked in any given position by finger nuts 19—19, which also serve the further function of preventing any leakage through the holes in the portion 8 of the tube —1— for screws 85 14. The enlarged portion 8 of tube —1— is closed at opposite sides by wire screens 20—20, whereby to prevent the escape of soap 13 from members 12. Rubber washers 30, 31, and 32 are employed at the joints to 90 make air tight unions.

To operate the device, same is first connected to the nozzle 3 of a hose 4. A suitable brush as 7 is secured to the end 5 of the tube —1—. The cake of soap 13 is disposed 95 within members 12. End portion 5 of the tube —1— is then screwed to the enlarged portion 8 thereof and the water turned on. The water will pass through the tube —1—, moisten the cake of soap 13, whereby to 100 form a soap suds and then pass out through the holes 21 of the brush 7. In the event that only a little soap is needed, or no soap at all, as for rinsing purposes, the operator will then turn screws 14, which may be provided with serrated parts 22, and thereby move members 12 toward each other to any desired degree.

Figs. 4, 5, and 7, show a modification of the tube —1—, embodying an enlarged portion 35, which supports therein the outer member 36 of a container 39, by means of

brackets 37. Portion 35 of the tube —1— is adapted for the sleeved mounting of a correspondingly enlarged portion 38 of the tube —1—. Portion 38 supports therein the 5 said container 39, by means of brackets 40. The end portion 41 of the outer member 36 of the container 39 is made in hemispherical shape, whereby to offer little resistance to the passage of the water through the tube 10 —1—. The enlarged portion 35 of the tube —1— being separated from the enlarged portion 38 of the tube, the soap, which is cylindrical shaped, is disposed in container 39, whereupon portion 38 of the tube —1— 15 is fitted to portion 35 and the parts pushed together, so that the threads of the bushing 45 may engage the threads 46 on portion 35 of the tube —1—, and thereby hold said parts firmly in assembled position. The 20 part 38 of the tube —1— is permitted to turn independently of part 35 by reason of a circumferential lug 47 formed integral with portion 38, which lug engages in a loose manner a corresponding recess in bushing 45. If, when the parts are assembled, the 25 operator desires to regulate the quantity of soap in the water, he can do so by turning portion 38 of the tube —1—, so that the apertures 48 of the container 39 will register 30 to a greater or lesser degree with the apertures 50 of the outer member 36 of the container 39, which fact may be indicated by means of the arrow 51 registering with the properly marked line of the graduated scale 35 52. The scale 53 of bushing 45 may be aligned with the scale 52, on tube —1—. In Fig. 6 there is shown a brush 60 adapted to be connected to the outer end 5 of tube —1— for cleaning the floor of a building. The 40 end 61 of the container 39 is closed and the opposite end is open for the insertion of the soap. The enlarged portion 35 of the tube —1— may be disposed along said tube relative to the convenience of manipulation by 45 the hand of the operator.

Having thus described my invention what I claim as new and desire to secure by Letters Patent is:

1. In an automobile washer, a tube, a hose 50 connected to one end of said tube, a brush

connected to the opposite end of said tube, means for holding soap subject to the action of water as same passes through said tube, and means for regulating the quantity of soap in said water.

55

2. In an automobile washer, the combination of a tube, means having apertures in said tube for holding a cake of soap, means for opening or closing said apertures in said means for holding said soap, and a brush, 60 substantially as described.

3. In an automobile washer, a tube, a hose connected to one end of said tube, a brush detachably connected to the opposite end of said tube, an apertured soap container for 65 holding a cake of soap within said tube, and means for adjusting the degree of opening of said apertures.

4. In an automobile washer, a tube, a hose connected to one end of said tube, a brush 70 detachably connected to the opposite end of said tube, members for holding a cake of soap within said tube, and means for adjusting said members with reference to each other.

5. In an automobile washer, the combination of a tube, having an enlarged portion, a second enlarged portion of said tube, said second portion adapted to sleeve said first named enlarged portion, an apertured soap 80 container supported within said enlarged portions, apertures in said soap container, and means for regulating the degree of opening of said apertures.

6. In an automobile washer, the combination of a tube, having an enlarged portion, a second enlarged portion of said tube adapted to sleeve said first named portion, an apertured soap container supported within said enlarged portion, and said enlarged 90 portions adapted to turn relative to each other for opening or closing the apertures in said soap container.

In testimony whereof I have affixed my signature in the presence of two witnesses. 95

HARRY M. JENNINGS.
